UNITED STATES PATENT OFFICE

GUSTAF HAMMER, OF CHICAGO, ILLINOIS, ASSIGNOR TO INTERNATIONAL HARVESTER COMPANY, A CORPORATION OF NEW JERSEY

GRAIN BINDER

Application filed October 20, 1930. Serial No. 489,790.

The invention relates to improvements in grain binders.

These machines embody a grain binding deck with which is associated a butter to line up the butt ends of the grain, so that better bundles will result. It is found that with present constructions of harvesters the butter is difficult to support and, as a result, objectionable sagging of the butter develops, which makes it difficult properly to operate the same.

Accordingly, the invention more specifically relates to an improved butter construction for a grain harvester.

15 The objects of the invention are to provide an improved supporting means for the butter and generally to improve the operation thereof by preventing objectionable sagging.

These desirable objects may be achieved 20 by the structure illustrated in the accompanying drawings, in which:

Figure 1 is a front elevational view of so much of a grain binder as is necessary to illustrate the invention; and

25 Figure 2 is a plan view of the structure shown in Figure 1.

A part of a grain binder frame is shown at 10 carrying a bracket 11, to which is connected the elevator 12, in the upper end of 30 which is journaled the usual conveyor drive shaft 13 carrying, in the usual manner, the bevel gear 14 which drives a bevel gear 15 carried at the lower end of a crank shaft 16, suitably supported on the bracket 11 and 35 frame piece 10. The bracket 11 has connected to it a downwardly inclined lower binder deck 17. At the lower end of the binder deck, the frame of the binder carries the usual binder frame 18, the upper end of 40 which is provided with a bracket 19.

The upper end of the crank 16 carries a sleeve 20, which sleeve includes a bifurcated extension 21 secured to a butter board 22 carrying the usual butt engaging elements 45 23. The outer end of said board 22 carries a bracket 24, in which is carried a shaft 25 connected by a cross brace 26 including bearings 27, in which is journaled a cranked outer end 28 of a supporting shaft 29, which 50 has its inner end bent downwardly, as at

30, and carried in suitable bearings 31 in the bracket 11. The shaft 25 pivotally carries a butter board extension 32, the front outer face of which carries a slotted bracket 33, through which slides a strip 34 connected by a bifurcated bracket 35 to the shaft 28.

The upper end of the bracket 11 carries an extension 36, and a brace rod 37 is connected between said bracket 36 and the bracket 19 in a manner to support the outer end of the binder frame 18. The upper end of the bracket 11 also carries a slotted bracket 38, through which is passed a push and pull bar 39 having a handle 40 accessible to the operator on his seat, which bar 39 is connected to an angle bar continuation 41 that is bent downwardly, as at 42, and made fast, as at 43, to the bifurcated bracket 35 herefore described. By pulling or pushing on the handle 40, the operator can move the butter mechanism forwardly or backwardly with respect to the grain deck 17, properly to set the butter in accordance with varying lengths of grain being handled. The upper binder deck is conventionally supported and 75 appears at 44.

So much of the structure described is standard practice in the grain binder art, and here it will be seen that the weight of the butter mechanism is carried by the crank 80 shaft 29 and the adjusting bars 39, 41. It is found that by such inadequate supports the butter eventually sags and in operation drags across the binder deck 17, which seriously interferes with its proper function. Accordingly, this invention provides additional supporting means for the butter mechanism, which will now be described.

A bail member 45 has one leg 46 connected at 43 to the downward extension 42 of the bar 41, and has its other leg 47 connected to the bar 41, as shown. This bail 45 is passed through a ring 48 carried by the brace rod 37, and accordingly it can be seen that the bail 45 is slidably supported by the brace 37 and, in turn, its legs, through the bar 41, function to support the butter and relieve the weight thereof from the crank shaft 29. It also relieves the adjusting rod 39 from carrying the weight of the butter 110

and, as a result, adjustment of the butter can more easily be effected. To provide a better sliding action of the adjusting bar 39, a slide shoe 49 is provided underneath 5 the bar 41, as shown in Figure 1, so that the shoe 49 will slide across the top of the upper binder deck 44.

In operation, the gearing 14, 15 causes the crank 16 to turn and impart to the board 10 22 an orbital movement, which is communicated to the extension 32, while the crank 28 merely serves as a swinging support for the parts. This swinging support is relieved of most of its supporting duty by the improved support 45 described, which is hung 15 from the supporting brace 37 and, because of this construction, the shifting rod 39 is also relieved of supporting duty and can, therefore, be more easily manipulated for adjustably setting the butter board mechanism. 20

From this detailed description, it must now be apparent that an improved construction has been provided, which achieves all of the desirable objects heretofore recited.

25 The illustrative example herein chosen for purposes of disclosure is obviously susceptible of changes and modifications without departing from the spirit and scope of the invention as expressed in the following 30 claims.

What is claimed is:

1. In a grain binder a main frame, a binder deck carried thereby, a brace extending above said deck, a butter extending across the deck, 35 means for supporting and driving the butter, means connected to the butter for setting the butter in various positions of adjustment relative to the deck, and means suspended from the brace providing an additional support for 40 the butter.

2. In a grain binder, a main frame, a binder deck carried thereby, a brace extending above said deck, a butter extending across the deck, means for supporting and driving 45 the butter, means connected to the butter for setting the butter in various positions of adjustment relative to the deck, and means suspended from the brace and having sliding movement relative thereto providing an additional support for the butter. 50

3. In a grain binder, a main frame, a binder deck carried thereby, a binder frame, a brace connected between the main and binder frames extending above said deck, a butter 55 extending across the deck, means for supporting and driving the butter, means connected to the butter for setting the butter in various positions of adjustment relative to the deck, and means suspended from the brace providing an additional support for 60 the butter.

4. In a grain binder, a main frame, a binder deck carried thereby, a brace extending above said deck, a butter extending across the 65 deck, means for supporting and driving the

butter, means comprising a bar connected to the butter for setting the butter in various positions of adjustment relative to the deck, and means suspended from the brace and connected to said bar providing an additional support for the butter. 70

5. In a grain binder, a main frame, a binder deck carried thereby, a binder frame, a brace extending above said deck and connected between the main and binder frames, a butter extending across the deck, means for supporting and driving the butter, means comprising a bar connected to the butter for setting the butter in various positions of adjustment relative to the deck, means suspended from the brace and connected to said bar providing an additional support for the butter, and means providing a connection between the suspending means and bar to permit relative sliding movement between the 80 bar and said means. 85

6. In a grain binder, a main frame, a binder deck carried thereby, a binder frame, a brace connected between said two frames and extending across said deck, a butter operable 90 over the deck, means for supporting and driving the butter, means connected to the butter for setting the butter in various positions of adjustment relative to the deck, and a bail suspended from the brace and connected to the adjusting means to provide an 95 additional support for the butter. 100

7. In a grain binder, a main frame, a binder deck carried thereby, a binder frame, a brace connected between said two frames and extending across said deck, a butter operable over the deck, means for supporting and driving the butter, means connected to the butter for setting the butter in various positions of adjustment relative to the deck, a bail suspended from the brace and connected to the adjusting means to provide an additional support for the butter, and means slidably connecting the bail to said brace. 105

8. In a grain binder, a main frame, a lower binder deck and an upper binder deck carried thereby, a brace extending across said upper deck, a butter operable between the decks, means for supporting and driving the butter, means connected to the butter for setting the 110 butter in various positions of adjustment relative to the deck, a shoe carried by the adjusting means to slide on the upper deck, and means suspended from the brace for sliding movement and connected to the adjusting means to provide an additional support for the butter. 115

9. In a grain binder, a main frame, a binder deck carried thereby, a binder frame, a brace connected between said two frames and extending across said deck, a butter operable over the deck, means for supporting and driving the butter, means connected to the butter for setting the butter in various positions of adjustment relative to the deck, means comprising a bar connected to the butter for setting the butter in various positions of adjustment relative to the deck, and means suspended from the brace and connected to said bar providing an additional support for the butter. 125

sitions of adjustment relative to the deck, a
bail carried by the adjusting means to move
therewith, and a device for slidably suspend-
ing the bail from the brace to provide addi-
5 tional support for the butter.

In testimony whereof I affix my signature.

GUSTAF HAMMER.
